METHOD AND APPARATUS FOR CONCENTRATING PULP WATER

Application filed January 22, 1929, Serial No. 334,266, and in Norway June 30, 1928.

In several industries and particularly in the paper manufacture the problem exists to remove from pulp water a proportion of its water content in order to render the mass more suitable for further treatment. This process, viz: the concentration of the pulp water, is usually carried out in special apparatus straining off a proportion of the water in order to leave the pulp at the desired degree of concentration. Ordinarily rotating strainers or screws are used, on the exterior cylindrical sieve cloth of which a part of the fibres is deposited, whereas the more or less clean water passes through the sieve surface into the strainer drum in order to be conducted away. The deposited layer is removed from the drum in some suitable manner.

In apparatus of this kind it is difficult to prevent some fibres from following with the water passing through the sieve member.

According to the present invention the problem has been solved in the manner that from the dilute fibre pulp which in well-known manner is introduced into a vessel or container with a movable sieve cloth, water is drained off upon sections above the sieve, and the pulp deposited upon the sieve cloth during its travel under each section is scraped off and is conducted into a compartment located at the end of each section and is removed from the compartment together with the simultaneously introduced water or pulp water.

Preferably not the whole of the deposited layer is scraped off, but a quite thin layer is left which passes to the next section in order to produce therein a commencing filtering layer preventing the fine fibres in the pulp water from passing through the sieve member.

The compartment receiving the concentrated pulp water is preferably maintained completely submerged in the pulp water of the container, so that the concentrated pulp water is removed from the compartments under hydrostatic pressure.

The method forming the subject matter of the present invention is preferably carried out in an apparatus, wherein above a travel-

ling sieve member which is completely or partly immersed in the dilute fibre pulp a series of compartments are distributed suitably apart along the submerged portion of the sieve member, said compartments at the side, where the sieve member travels in, being located at a suitable distance from the sieve member so as to allow the layer deposited upon the member to travel into the compartment, whereas each compartment at the opposite side, where the sieve member travels out, forms or is provided with a scraper which may be adjusted to the sieve member and may operate to loosen therefrom the deposited fibres save in case the quite thin layer to be left.

A simple construction is obtained by making the compartments in the form of pipes which are provided with a longitudinal opening along the portion facing the exterior side of the sieve member, said pipes being provided at one or both ends with outlets for the concentrated pulp mass. The pipes may be arranged adjustably about their axes, so that the distance of the two edges of the longitudinal aperture from the sieve member may be adjusted by rotating the pipes.

The simplest construction of the apparatus is obtained, when the compartments are distributed on the exterior periphery of an ordinary strainer drum which together with the compartments is completely submerged in the pulp water, so that water drained off is removed in ordinary manner from the drum inside, whereas concentrated pulp water is conducted out separately through the exterior compartments.

If desired the interior of the strainer drum may be subjected to suction, whereby the draining capacity of the drum is increased.

The invention is illustrated in the accompanying drawings, wherein Figure 1 shows diagrammatically in longitudinal section a plane sieve member with associated compartments. Figure 2 shows a portion of a cylindrical sieve member with pipe compartments in cross section. Figure 3 is an essentially diagrammatic cross section and Figure 4 a longitudinal section of a concentrating strainer drum in a practical construc-

tion. Figure 5 is a longitudinal section of another construction.

The principle of the invention will be understood from Figure 1. An endless sieve cloth 1, only a part of which is shown in the drawings, travels slowly in the direction of the arrow and forms a straight portion between the rollers 2 and 3. Above this portion a number of compartments 4 is arranged 10 suitably apart and preferably in the form of pipes with longitudinal slots 5 (see Figure 2), supporting rollers 6 for the sieve member 1 being arranged under each pipe. Above the sieve cloth 1 and opposite the rollers 2, 3 15 larger rollers 7, 8 respectively are arranged serving to limit both ends of a space 9 which is closed in suitable manner (not shown) along both sides, so that the space 9 forms a suitably deep vessel or container having as a 20 bottom the travelling sieve cloth 1. The vessel 9 is supplied with the dilute pulp mass.

By rotation the pipes 4 may be so adjusted that the longitudinal edge of the aperture 5, where the sieve cloth travels into the pipe, is 25 maintained at a somewhat larger distance from the sieve cloth 1 than the opposite longitudinal edge which is maintained in contact with or at a quite small distance from the cloth. The thickness of the pulp layer deposited on the upper side of the cloth 1 will 30 therefore increase during its travel from the outlet of one compartment 4 towards the lowermost edge of the slot 5 in the next compartment. The layer is scraped off by this edge 35 and is distributed in the water which is inside the pipe 4 and will form therein a concentrated pulp water which is passed out to the sides through each of the pipes. However, if the lowermost edge of each aperture or slot 5 40 is not quite in contact with the sieve cloth 1, the layer is not scraped off completely. A quite thin film is left which will operate as a commencing filter after the sieve cloth has passed out from each pipe 4. This filter prevents even the finest particles (the flour particles) from passing through the member 1, so that only clean water is strained off and is 45 passing down through the sieve cloth.

The concentrated pulp water in the compartments 4 cannot, on account of the hydrostatic pressure, escape back into the vessel 9 again, but it must follow out to the outlet of the pipes and will consequently be positively separated from the dilute pulp water, 55 and in this manner a continuous operation is obtained without difficulty.

According to Figure 2 the compartments 4 are distributed exteriorly around a cylindrical strainer drum 1. The construction of this drum may be as indicated in Figures 3 and 4. The sieve cloth 1 is stretched between the end walls 10, 11, the hubs 12, 13 of which are keyed to a rotating shaft 14 supported by stationary bearings and placed in 65 a slow rotation.

The end wall 11 has a central outlet 15 for clean water which has been strained off. The outlet 15 may be subjected to suction. The pipes 4 which constitute the concentrating compartments are rotatably supported by the stationary end walls 16, 17 forming the vessel 9 and at both ends the pipes are open or connected with conduits for carrying off and collecting the concentrated pulp water from the compartments.

It will be understood that the construction may be varied in several manners without departing from the principle of operation described.

According to Figure 5 the cylindrical sieve cloth 1 is attached to three spoke crosses 18, 19, 20 each of which is keyed to the shaft 14. This shaft is supported by the stationary end walls 21, 22 of the drum, one of which is provided with a stationary outlet 23 for the water drained off. 24 is the driving wheel (gear wheel) of the shaft. By this construction the hollow pivot in the drum end wall 11 of Figure 4 is avoided.

I claim:

1. Method of concentrating pulp water, particularly fibre pulp for paper making and the like, by straining off water from dilute fibre pulp, characterized by this that the dilute fibre pulp is introduced into a container having a travelling sieve cloth, water is strained off upon sections above the cloth, the mass deposited as a layer upon the cloth during its travel under each section is scraped off completely and is conducted into a compartment located at the end of each section and is passed out from the compartment together with water or pulp water received simultaneously in the said compartment.

2. Method of concentrating pulp water, particularly fibre pulp for paper making and the like, by straining off water from dilute fibre pulp, characterized by this that the dilute fibre pulp is introduced into a container having a travelling sieve cloth, water is strained off upon sections above the cloth, the mass deposited as a layer upon the cloth during its travel under each section is scraped off partly, the portion scraped off being conducted into a compartment located at the end 115 of each section and is passed out from the compartment together with water or pulp water received simultaneously in the said compartment, whereas the portion of the layer left on the sieve cloth is passed to a 120 next section so as to constitute therein a commencing fibre layer preventing the fine fibres contained in the pulp water from passing through the cloth.

3. In an apparatus for concentrating pulp water, particularly fibre pulp for paper making and the like, the combination of a container, the walls of which are constituted partly by a travelling sieve cloth, means for supplying dilute pulp water to said container,

- means defining a compartment arranged in the container near that end of the wall constituted by said cloth and open to the container and provided with separate outlet, and 5 a scraper formed on said compartment means, adapted to scrape off inside the compartment the pulp layer deposited upon the cloth.
4. In an apparatus for concentrating pulp water, particularly fibre pulp for paper making and the like, the combination of a container having walls constituted partly by a travelling sieve cloth, means for supplying dilute pulp water to said container, a number of compartments distributed apart in the container in proximity to the cloth and open to the container, a scraper formed on each compartment and adapted to scrape off from the cloth a suitable quantity of the pulp deposited on the cloth and to deliver this pulp 10 quantity in the associated compartment so as to produce therein concentrated pulp water, and outlet means on each compartment for separately removing said concentrated pulp water therefrom.
- 15 5. In an apparatus for concentrating pulp water, particularly fibre pulp for paper making and the like, the combination of a container having walls constituted partly by a travelling sieve cloth, means for supplying dilute pulp water to said container, a compartment totally submerged in the container in proximity to the cloth and open to the container, a scraper formed on said compartment adapted to scrape off from the cloth a 20 suitable quantity of the pulp deposited on the cloth and to deliver this pulp quantity in the said compartment so as to produce therein concentrated pulp water, and outlet means on each compartment for separately removing said concentrated pulp water therefrom.
- 25 6. In an apparatus for concentrating pulp water, particularly fibre pulp for paper making and the like, the combination of a container having walls constituted partly by a travelling sieve cloth, means for supplying dilute pulp water to said container, a compartment submerged in the container in proximity to the cloth and open to the container, a scraper formed on said compartment adapted to scrape off from the cloth a 30 suitable quantity of the pulp deposited on the cloth and to deliver this pulp quantity in the said compartment so as to produce therein concentrated pulp water, and outlet means on each compartment for separately removing said concentrated pulp water therefrom.
- 35 7. In an apparatus for concentrating pulp water, particularly fibre pulp for paper making and the like, the combination of a container having walls constituted partly by a travelling sieve cloth, means for supplying dilute pulp water to said container, a compartment submerged in the container in proximity to the cloth and open to the container and cloth at the side facing towards the incoming cloth portion, a scraper formed on 40 said compartment, at its opposite side, where the cloth travels out, said scraper being adapted to scrape off from the cloth a suitable quantity of the pulp deposited on the cloth and to deliver this pulp quantity in the said compartment, so as to produce therein concentrated pulp water, and outlet means on 45 said compartment for separately removing said concentrated pulp water from the compartment.
- 50 8. In an apparatus for concentrating pulp water, particularly fibre pulp for paper making and the like, the combination of a container having walls constituted partly by a travelling sieve cloth, means for supplying dilute pulp water to said container, a stationary pipe submerged in the container and having a longitudinal aperture facing towards the cloth near the portion thereof travelling out from the container, the edge of the aperture at which the cloth arrives being arranged at some small distance from the sieve cloth, whereas the opposite edge is adapted to operate as a scraper to scrape off from the cloth a suitable quantity of the pulp deposited on the cloth and to deliver this pulp quantity in the pipe so as to produce therein concentrated pulp water, said pipe having an outlet for separately removing said concentrated pulp water therefrom.
- 55 9. In an apparatus for concentrating pulp water, particularly fibre pulp for paper making and the like, the combination of a container having walls constituted partly by a travelling sieve cloth, means for supplying dilute pulp water to said container, a stationary pipe submerged in the container and having a longitudinal aperture facing towards the cloth near the portion thereof travelling out from the container, the edge of the aperture at which the cloth arrives being arranged at some small distance from the sieve cloth, whereas the opposite edge is adapted to operate as a scraper to scrape off from the cloth a suitable quantity of the pulp deposited on the cloth and to deliver this pulp quantity in the pipe so as to produce therein concentrated pulp water, said pipe having an outlet for separately removing said concentrated pulp water therefrom, and means for adjusting the pipe around its longitudinal axis so as to enable the quantity of deposited layer scraped off to be adjusted between zero and complete.
- 60 10. In an apparatus for concentrating pulp water, particularly fibre pulp for paper making and the like, the combination of a container having walls constituted partly by a travelling sieve cloth, means for supplying

- dilute pulp water to said container, a number of stationary pipes submerged in the container and distributed mutually apart in proximity to the cloth and having each a longitudinal aperture facing towards the cloth, the edge of the aperture at which the cloth arrives being arranged at some small distance from the sieve cloth, whereas the opposite edge is adapted to operate as a 5 scraper to scrape off from the cloth a suitable quantity of the pulp deposited on the cloth and to deliver this pulp quantity in the associated pipe so as to produce therein concentrated pulp water, said pipe having an 10 outlet for separately removing said concentrated pulp water therefrom, and means for adjusting each pipe around its longitudinal axis so as to enable the quantity of deposited 15 layer scraped off in each pipe to be adjusted between zero and full.
11. In an apparatus for concentrating pulp water, particularly fibre pulp for paper making and the like, the combination with a container of a strainer drum submerged therein, 20 means for rotating the drum; means for removing water from the interior of the drum, a number of stationary pipes submerged in the container and distributed mutually apart in proximity to the cloth and having each a longitudinal aperture facing towards the cloth, the edge of the aperture at which the cloth arrives being arranged at some small distance from the sieve cloth, whereas the opposite edge is adapted to operate as a scraper 25 to scrape off from the cloth a suitable quantity of the pulp deposited on the cloth and to deliver this pulp quantity in the pipe so as to produce therein concentrated pulp water, said pipes each having an outlet for separately removing said concentrated pulp water from the pipes.
12. In an apparatus for concentrating pulp water, particularly fibre pulp for paper making and the like, the combination with a container of a strainer drum submerged therein, 30 means for rotating the drum, means for removing water from the interior of the drum, means for establishing a reduced pressure inside the drum, stationary compartments distributed outside the drum in proximity to its sieve cloth and open towards the same, a scraper formed on each compartment and 35 adapted to scrape off from the cloth a suitable quantity of the pulp deposited on the cloth and to deliver this pulp quantity in the associated compartment so as to produce therein concentrated pulp water, and outlet means on said compartment for separately removing said concentrated pulp water from each compartment.
13. In an apparatus for concentrating pulp water, particularly fibre pulp for paper making and the like, the combination with a container of a strainer drum submerged therein, 40 means for rotating the drum, means for removing water from the interior of the drum, means for establishing a reduced pressure inside the drum, stationary compartments 45 distributed outside the drum in proximity to its sieve cloth and open towards the same, a scraper formed on each compartment and adapted to scrape off from the cloth a suitable quantity of the pulp deposited on the cloth and to deliver this pulp quantity in the associated compartment so as to produce therein concentrated pulp water, and outlet means on said compartment for separately removing said concentrated pulp water from each compartment.
14. In an apparatus for concentrating pulp water, particularly fibre pulp for paper making and the like, the combination with a container of a strainer drum submerged therein, 50 means for rotating the drum, means for removing water from the interior of the drum, a number of stationary pipes submerged in the container and distributed mutually apart in proximity to the cloth and having each a longitudinal aperture facing towards the cloth, the edge of the aperture at which the cloth arrives being arranged at some small distance from the sieve cloth, whereas the opposite edge is adapted to operate as a scraper 55 to scrape off from the cloth a suitable quantity of the pulp deposited on the cloth and to deliver this pulp quantity in the pipe so as to produce therein concentrated pulp water, said pipes each having an outlet for separately removing said concentrated pulp water from the pipes.
15. In an apparatus for concentrating pulp water, particularly fibre pulp for paper making and the like, the combination with a container of a strainer drum submerged therein, 60 means for rotating the drum, means for removing water from the interior of the drum, a number of stationary pipes submerged in the container and distributed mutually apart in proximity to the cloth and having each a longitudinal aperture facing towards the cloth, the edge of the aperture at which the cloth arrives being arranged at some small distance from the sieve cloth, whereas the opposite edge is adapted to operate as a scraper 65 to scrape off from the cloth a suitable quantity of the pulp deposited on the cloth and to deliver this pulp quantity in the pipe so as to produce therein concentrated pulp water, said pipes each having an outlet for separately removing said concentrated pulp water from the pipe, and means for adjusting each pipe around its longitudinal axis so as to enable the quantity of deposited layer scraped off in each pipe to be adjusted between zero and full.

In testimony whereof I have signed my name unto this specification.

OTTO ANDRESEN.
